UNITED STATES PATENT OFFICE.

CHARLES THORP GOEWY, OF SOUTH BEND, INDIANA.

PARCEL-POST CASE.

1,190,148.

Specification of Letters Patent.

Patented July 4, 1916.

Application filed October 1, 1915. Serial No. 53,512.

To all whom it may concern:

Be it known that I, CHARLES T. GOEWY, a citizen of the United States, and a resident of South Bend, in the county of St. Joseph and State of Indiana, have invented a new and useful Improvement in Parcel-Post Cases, of which the following is a specification.

This invention is an improvement in parcels carriers and consists in certain novel constructions, combinations and arrangements of parts as will be hereinafter described and claimed.

Among the objects of my invention is to provide transporting means which will bear both sending and return addresses so positioned thereon that but one is visible when the carrier is ready for shipment.

Another object is to provide retaining means for the articles to be carried that shall be capable of being secured together so as to insure safe transportation of said articles.

Other objects will appear in the detailed description.

In the drawings, which constitute part of this application, and in which the same reference numerals refer to the same parts, Figure 1 is a perspective view of my carrier. Fig. 2 is a section thereof on line 2-2 of Fig. 1, in the direction of the arrows. Fig. 3 is a section thereof on line 3-3 of Fig. 1 in the direction of the arrows. Fig. 4 is an enlarged isometric projection of my carrier shown open so that the nature of its construction may be readily ascertained. Fig. 5 is a broken view of one of the flaps showing the position of an address slip, and Fig. 6 is a section on line 6-6 of Fig. 4, showing the construction whereby the cover is retained in position.

The practical embodiment of my invention shown in said drawings comprises a rigid body portion 1 formed preferably of well-known cellular board. It is composed of end members 2 and side members 3 suitably secured together as by gluing. Said end members are provided with flaps 4 whose combined length is less than the length of the body portion so they do not meet when folded down. (See Fig. 3.) Side members 3 are provided with flaps 5 so proportioned that when folded inward toward each other considerable portions overlap as shown in Fig. 2.

6 is a suitable covering preferably made

of heavy canvas shaped to conform with the superficial outlines of body portion 1 and provided with flaps 7 having pockets 8 at their inner extremities within which flaps 5 engage. Addressing labels 14 (Fig. 1) are pasted on the canvas flaps 7 adjacent to the longitudinal and free side edges of the flaps, as shown in Fig. 5. Thus, when said flaps 5 are folded, one of the addresses is concealed by the overlapping one. Said covering is also provided with flaps 9 which overlap when closed. Said flaps 9 are supplied with suitable securing means as indicated at 10 and 11. Retaining means 12, preferably straps provided with fastening means 13, are suitably secured to covering 6.

My device may be employed for various uses but is especially desirable for such cases as the sending home of laundry by students. In such use the flap bearing the home address will be uppermost, thus covering the student's address. When the finished laundry is returned, the other flap will be uppermost, so that the home address will be obscured.

It will be readily seen that my device is capable of extended use in the parcels post service and will be especially useful in the development of the hamper traffic, and the direct supply of goods from producer to consumer in that it will do away with the use of the ordinary perforated tag so liable to become detached.

I claim:

1. A parcels carrying device, substantially as herein described, comprising an inner section composed of a box having end flaps and side flaps, the latter being of combined width greater than the width of the box whereby they will overlap when closed, and a flexible cover comprising a box-like portion adapted to receive the inner section and having end flaps corresponding to the end flaps thereof and also having side flaps corresponding to the side flaps of the inner section, these side flaps of the cover being of a combined width greater than the width of the carrier, whereby they will overlap when closed, addresses on the outer side of both side flaps of the cover, near the free edges thereof, each address being substantially covered by the overlapping portion of the flap bearing the other address when the flaps are closed, and fastening devices, all substantially as and for the purpose set forth.

2. In a parcels carrying device, the combination of a rigid body portion bearing a plurality of oppositely disposed cover flaps, two of which flaps overlap, a textile cover shaped to conform therewith, and provided with oppositely disposed flaps, two of which overlap and are provided with pockets, said cover being detachably secured to said body portion by means of said pockets, which are adapted to retain said two overlapping flaps and adapted to bear address labels adjacent their edges, said other two flaps of said cover being adapted to be secured at their meeting ends disposed at right angles to said overlapping flaps, and binding means disposed around said covering and attached thereto.
3. In a parcels carrying device, the combination of a rigid body portion provided with closing flaps, a flexible covering shaped to conform with said body portion and detachably secured to certain of said flaps, and binding means attached to said covering.
4. In a parcels carrying device, the combination of a body portion, provided with closing flaps, a covering shaped to conform with said body portion and secured to cer-

tain of said flaps, and binding means attached to said covering.

5. A shipping container comprising an inner case provided with overlapping flaps, a textile outer cover having corresponding overlapping flaps adapted to bear address labels and provided with pockets at their extremities, said pockets adapted to fit over the overlapping flaps of said case.

6. A shipping container comprising an inner case provided with overlapping flaps, an outer cover having corresponding overlapping flaps, adapted to bear address labels at their extremities, and provided with retaining means to engage the overlapping flaps of said case.

7. A shipping case provided with a cover consisting of side and end folding flaps, the side flaps bearing each an addressed label and being each of greater width than half the body of the box, so that one section is partly covered and concealed by the other which overlaps it, as described.

CHARLES THORP GOEWKEY.
